UNITED STATES PATENT OFFICE.

LEE S. CHADWICK, OF SHAKER HEIGHTS, OHIO, ASSIGNOR TO THE CLEVELAND METAL PRODUCTS COMPANY, OF CLEVELAND, OHIO, A CORPORATION OF OHIO.

AUTOMATICALLY ADJUSTED WICK STOP FOR OIL BURNERS.

Application filed February 26, 1921, Serial No. 448,108. Renewed June 6, 1923.

To all whom it may concern:

Be it known that I, LEE S. CHADWICK, a citizen of the United States, residing at Shaker Heights Village, in the county of Cuyahoga and State of Ohio, have invented a certain new and useful Improvement in Automatically Adjusted Wick Stops for Oil Burners, of which the following is a full, clear, and exact description, reference being had to the accompanying drawings.

This invention relates to oil burners of the class employing wicks and incorporating means for raising and lowering the wick.

The principal objects of the invention are to provide means for stopping the wick in "high" position and which automatically adjusts itself to compensate for the variable length of the wick due to its being cleaned or trimmed; to provide an adjustment for said means through which the "high" position of the wick may be varied; and to provide a device through which said means may be rendered ineffective so that the wick may be removed from the burner.

Further and more specific objects are the provision of a comparatively simple and durable construction through which the ends sought to be attained are effectually accomplished with certainty of action; and which affords convenience of manipulation and adjustment.

These several objects, and others which will become apparent as this description proceeds are attained in the embodiments illustrated in the accompanying drawings, described in detail hereinafter, and finally set out in the claims annexed hereto.

In the drawings, Fig. 1 is a central vertical section through a burner embodying one form of my invention; Fig. 2 is a sectional plan on the line 2—2 of Fig. 1; Figs. 3 and 4 are views similar to Fig. 1 but less extensive, which show, respectively, the stop in effective position, restricting the wick against being elevated above "high" position; and in ineffective position, under which condition the wick may be removed from the burner; Fig. 5 is a central vertical section through a burner embodying another form of my invention, the stop being shown in effective position in dotted lines; Fig. 6 shows the stop tripped to release the wick

so that it may be removed from the burner; Figs. 7 and 8 are central vertical sections through a burner, in planes at right angles to each other, which incorporates a further modification of the invention; and Fig. 9 is a sectional view, similar to Fig. 7, showing the stop in effective position.

I have shown my invention incorporated in burners of the type comprising inner and outer wick tubes between which a cylindrical wick is guided. In Figs. 1 to 4, the outer wick tube is designated 1 and the inner wick tube 2, and at their lower ends they are connected by a wall 3 so as to enclose a space 4 within which the wick 5 is contained. The wick is equipped with a carrier 6 which surrounds the lower portion of the wick and is attached thereto by having its lower edge formed or crimped about the lower edge of the wick, as indicated at 7.

Spaced vertical walls 10 extend transversely across the inner wick tube and enclose a space which communicates with the wick space through the slots 11 in said tube. A beam 12 is arranged to move vertically within the space between the walls 10 and at its ends has fingers 13 that extend upwardly along the outer side of the wick carrier 6 and turn inwardly over the top thereof, as shown at 14. In this manner the wick is secured to the beam 12. A rod 15 has its lower end connected with the beam 12 and its upper end guided through an aperture in the top wall 16 that closes the space between the walls 10. A disk 20 is applied to the wall 16 and the same has its edge turned upwardly to provide a flange 21 into which the base of a flame spreader 22, shown in dotted lines, may be confined.

A lever 25, pivoted upon a pin 26 that is supported by and between the walls 10, is made up of two side plates that are connected at one end by a part 27 and are spaced apart at the opposite end by a weight 28, the side plates of the lever extending beyond said weight through a slot in the inner wick tube into the wick space where a roller 30 is supported between said plates on a pintle 31 and in a position to be engaged by the top of the wick when the wick is elevated.

Guided between walls 10 is a weight 35

which has a projecting portion 36 provided with an aperture 37 through which the rod 15 passes. When the parts are in normal position the weight 35 rests upon the lever 25, its lower portion being reduced in width to pass between the side plates of the lever. Pivoted between ears 38 which rise from the weight is an arm 39 having an aperture for the rod 15 and which is only slightly greater in diameter than the rod. The end of the arm 39 adjacent the rod is turned down at 40 to engage the end of the extension 36, while its opposite end has an abutment 41 within which a screw 42 is threaded. The arm 39 may be so balanced that it has a tendency to tip upwardly at its end adjacent the rod 15 and this action is encouraged by a spring 43 that is compressed between said end of the arm and the portion 36 of the weight. While the weight 35 rests upon the lever 25, the part 27 of the lever engages the abutment 41 and prevents the arm 39 from rocking or tilting in the direction just mentioned.

The upper end of the rod 15 has secured to it the corresponding end of a rack 45 that extends downwardly along the outer side of one of the walls 10 and is guided at its lower end through an extension of a bracket 46 that is carried by the burner structure and within which is journaled the inner end of a spindle 47 that carries a pinion 48 the teeth whereof mesh with the holes 49 in the rack 45. The spindle is further supported by a bracket 50, and it has a hand wheel 51 secured to its outer end. A driving connection is thus effected between the spindle 47 and the wick through pinion 48, rack 45, rod 15, beam 12, and fingers 13, so that when the spindle is rotated by means of the hand wheel 51 the wick may be adjusted within the wick space.

As the wick is elevated, its upper end engages the roller 30 and displaces it inwardly, swinging the adjacent end of the lever 25 upwardly and the part 27 thereof away from the abutment 41, allowing the arm 39 to rock upon its pivot and causing it to clutch the rod 15 by reason of its angular relation to the rod and the fact that its aperture is only slightly greater in diameter than said rod. Accordingly, as the rod 15 continues to rise, it will carry the arm 39 and parts associated and connected with it upwardly until the screw 42 engages the wall 16. The parts being thus stopped, the wick will be restricted against movement beyond "high" position. When the wick is retracted and the weighted end of the lever 25 swings downwardly as the roller 30 resumes its former position within the wick space, the weight 35 settles upon the lever 25 and the arm 39 returns to perpendicular relationship to the rod 15 because of the engagement of its abutment 41 with the part 27 of the

lever, thereby freeing itself from the rod and allowing the rod to descend with the wick to a lower position.

A lever 55 is disposed above the disk 20 and one of its ends curves downwardly through slots in said disk and in the wall 16 into the space between the walls 10. The lever is pivotally supported upon a pin 56. When it is desired to remove the wick from the burner, the outer end of this lever is thrown upwardly to swing its inner end into the path of the arm 39, in which position it is shown in Fig. 4, so that, when the parts are elevated, the screw 42 is prevented from engaging the wall 16 thereby allowing the weighted end of the arm 39 to rise and release the grip of the arm upon the rod 15. Consequently the wick carrying part may now be elevated until the upper ends of the fingers 13 are considerably above the corresponding end of the outer wick tube when the wick may be disengaged from said fingers and lifted out of the burner. During the removal of the wick, and in order to gain access to the lever 55 it is of course necessary to remove the spreader 22.

With reference to the second form of the invention, in Figs. 5 and 6 the outer and inner wick tubes are designated 1^a and 2^a, respectively, and the wick space between them is closed at its lower end by the wall 3^a. The wick is indicated at 5^a, the wick carrier at 6^a, and fingers 13^a connect the wick to the beam 12^a that is attached to the lower end of a rod 60. The rod operates within the space between the walls 10^a and in this space a lever 61 is pivotally supported upon a pin 62, the free end of the lever carrying a roller 63 which is adapted to be engaged by the wick 5^a when the latter is elevated. A weight 65 is guided between the walls 10^a and has an extension 66 that is provided with an aperture through which the rod 60 operates. The space between the walls 10^a is closed at its upper end by a wall 67 whereon is mounted a member 68 which serves to position the flame spreader 69, and the upper end of the rod 60 extends through an aperture in the wall 67. An L-shaped lever 70 is pivotally supported through ears 71 from the wall 67, and this lever projects upwardly through a slot 72 in said wall. The nose 73 of the lever 70 is adapted to pass through an opening 74 in the member 68 when the flame spreader 69 is removed. However, when the flame spreader is in position, it prevents the nose of the lever 70 from being projected in the manner stated so that said lever is restrained against appreciable movement. A rack 75 is connected to the upper end of the rod 60 and the same depends along one of the side walls 10^a and is guided at its lower end in a bracket 46^a, which bracket, with another designated 50^a, support a spindle 47^a that

carries at its inner end a pinion 48^a that meshes with the rack 75, and at its outer end a hand wheel 51^a.

When the spindle is rotated by means of 5 the hand wheel 51^a in a direction to elevate the wick through the connections comprised of the pinion 48^a, the rack 75, rod 60, and beam 12^a, the wick will engage the roller 63 and swing the lever 61 to the position indicated in dotted lines in Fig. 5. This will result in the weight 65 being tilted and its extension 66 clutching the rod so that in the further elevation of the rod the weight will be carried with it. The weight will 10 continue to rise until the adjusting screw 65^a engages the lever 70, as indicated in dotted lines in Fig. 5. The weight being thus stopped, the movement of the rod will be arrested and the wick will be restrained against 15 movement beyond "high" position.

When it is desired to remove the wick from the burner, the flame spreader 69 is removed from the positioning member 68 which will allow the lever 70 to swing upward with its nose projected through the opening 74 in the member 68, allowing further movement of the weight 65. As the weight so moves, the outer end of its extension 66 will engage an abutment 77 that is carried by the top wall 67 (see Fig. 6) and this will render the grip of the weight upon the rod 60 of no effect on account of the weight 65 being permitted to rise freely, and with the rod 60 thus released, the wick 20 may be projected high enough to expose the fingers 13^a above the wick tube 1^a when the wick may be disconnected from said fingers and lifted out of the burner.

In Figs. 7, 8 and 9, the elements of the burner are designated by the same reference numerals as those which refer to the corresponding parts in the preceding figures except that such numerals are augmented by the exponent *b*.

45 The spaced walls 10^b of the present modification are provided with shoulders or ledges 80. A rod 81 is connected at its lower end to the beam 12^b, and its upper end projects through an aperture in a top wall 82 and carries a cross pin 83. This pin has its ends connected with the branches of a yoke 84 which extends downwardly along the outer sides of the walls 10^b and is pivotally attached at 85 to a lever 86 which is fulcrumed at 87 in a bracket 88 that depends from the rear side of the burner, the free end of the lever terminating in a handle 89. It will be seen that through these connections the wick 5^b may be raised and lowered by lifting and depressing the lever 86. A block 90 has a vertical bore through which the rod 81 is slidable, and within a kerf or slot 91 which opens into the bore is pivoted, on a pin 92, a jaw 93 that is adapted to engage the adjacent side of the rod 81, said side be-

ing preferably roughened or serrated so as to enhance the gripping action. The jaw 93 is adapted to be rocked in one direction upon its pivot by a spring 94, one end of which is connected to the jaw and the other to a bracket 95 that is carried by the block 90. An adjusting screw 96 is threaded into the upper end of the jaw 93. A lever 98 is pivoted upon a pin 99 that is supported by and between the side walls 10^b in a position to project a roller 100 that is carried by said lever through a slot of the inner wick tube into the wick space so that as the wick is elevated it will engage the roller and displace it laterally to swing the lever 98. The lower 70 end of the lever 98 is connected through a link 101 with the jaw 93. When the wick is elevated and the lever is swung as aforesaid it will rock the jaw in a direction to engage its inner end with the side of the rod 81 so 75 that as the rod rises it will carry with it the block 90, the weight of the block increasing the grip of the jaw upon the rod. During the rise of the block 90, the free end of the link 101 will ride in the slot 102 in the jaw. 80 The parts will continue to rise with the rod until the screw 96 engages the depressed central portion of the top wall 82 (see Fig. 9) and such parts will be stopped to restrain the rod 81, and consequently the wick, 85 against further elevation.

In order to disengage the parts from the rod 81 for the purpose of removing the wick, it is necessary to insert an instrument through a slot 103 in the wall 82 and release the jaw 93; and upon a disconnection of the parts, the wick may be elevated to expose the fingers 13^b when they may be disengaged from the wick and the wick lifted out. The depressed central portion of the 90 wall 82 serves to position a spreader 105.

It has already been said that the side of rod 81 (Figs. 7, 8 and 9) wherewith the jaw 93 engages, is preferably roughened or serrated to enhance the holding action between these parts. So, too, may the rod 18 of the first form and rod 60 of the second be roughened if desired and this may be effected in a very convenient manner by threading the rod, as indicated in connection with rod 60 in Figs. 5 and 6. As an obvious alternative of threading or serrating the rod, the same may be provided with a succession of closely spaced annular grooves or ridges. Any means of effecting a positive hold of the stop parts upon the rod is all that is required. The smooth rod is found to work quite satisfactorily in all the embodiments herein illustrated especially in those shown in Figs. 1 to 6.

In connection with this case, reference should be made to a companion application filed by me concurrently herewith and bearing Serial No. 448,109. Other applications relating to automatic wick stops which I 120

have more recently filed are Serial Nos. 528,813 and 528,814, dated January 12, 1922.

Having thus described my invention, what I claim is:—

- 5 1. In a burner of the class described, the combination with the wick, of a member movable therewith in a direction substantially parallel thereto, a device connectable to said member, means engaged and moved by the wick when the latter is elevated for effecting the connection of said device to the member, and a stop for limiting the movement of said device.
- 10 2. In a burner of the class described, the combination with the wick, of a member movable therewith, a device connectable to said member, means engaged and moved by the wick when the latter is elevated for effecting the connection of said device to the member, and an adjustable stop for limiting the movement of said device.
- 15 3. In a burner of the class described, the combination with the wick, of a member movable therewith in a direction substantially parallel thereto, a device connectable to said member, means engaged and moved by the wick when the latter is elevated for effecting the connection of said device to the member, means for limiting the movement 20 of the device, and further means for rendering the connection between the device and aforesaid member ineffective.
- 25 4. In a burner of the class described, the combination with the wick, of a member movable therewith in a direction substantially parallel thereto, a device having limited movement in the direction of movement of said member, and means engaged and actuated by the wick when the latter is elevated for effecting connection between the device and said member.
- 30 5. In a burner of the class described, the combination with the wick, of a member movable therewith in a direction substantially parallel thereto, a device having limited movement in the direction of movement of said member, means for clutching said device to the member so that it will move therewith, and further means engaged and actuated by the wick when the latter is elevated for rendering the former means effective.
- 35 6. In a burner of the class described, the combination with the wick, of a member movable therewith, a device engaged with said member, the member being capable of independent movement with respect to said device when the device holds a given annular relation to the member, the member and device moving together upon said device assuming a different angular relation to the member, means wherewith the device is adapted to cooperate and through which an angular relationship between said device and member is effected that affords independent

movement between the member and device, said means being arranged to be engaged and moved by the wick thereby to alter the angular relationship between the device and member whereby the device is caused to move with the member, and a stop for limiting the movement of the device.

7. In a burner of the class described, the combination with the wick, of a member movable therewith, a device engaged with said member in such manner as to be independent of movement therewith when in a position substantially perpendicular to the member but which clutches said member and is accordingly movable therewith when in other than perpendicular relationship to the member, an element wherewith said device cooperates when in normal position and by means of which it is retained substantially perpendicular to the member, said element being arranged to be engaged and moved by the wick when the latter is elevated thereby to change the angular position of the device with respect to the member and means for limiting the movement of the device.

8. In a burner of the class described, the combination with the wick, of wick raising mechanism, operative connections between said mechanism and the wick and involving a member that is movable with the wick, a device loosely engaged with said member and independent therefrom as to movement when occupying a position substantially perpendicular to said member but acting to 100 clutch said member so as to be movable therewith when in other than perpendicular relationship to the member, a support for the device whereby it is sustained in substantially perpendicular relationship to the member, said support being arranged to be engaged and moved by the wick when the latter is elevated to impart to said member a position other than one perpendicular with respect to the member whereby the device is caused to clutch the member, and a stop for limiting the movement of the device.

9. In a burner of the class described, the combination with the wick, of wick raising mechanism involving a rod, a device having an aperture through which the rod extends and which is capable of movement in the direction of movement of the rod, said device being free from the rod when in substantially perpendicular relationship thereto but which is so balanced as to assume an angular relationship with respect to the rod thereby to clutch the same when suspended solely from the rod, a stop for limiting the movement of the device and cooperating therewith in such manner as not to disturb the clutching of the rod by said device, a second stop wherewith the device cooperates in such manner as to re- 115 120 125 130

lease the device from the rod, one of said stops being movable from effective position, and means for supporting the device when in normal position in perpendicular relationship to the rod, said means being arranged to be engaged and moved by the wick when the latter is elevated thereby to permit the device to assume other than perpendicular relationship to the rod.

10. 10. In a burner of the class described, the combination with the wick, of wick raising mechanism involving a rod, a device having an aperture through which the rod extends and which is capable of movement in the direction of movement of the rod, said device being free from the rod when in substantially perpendicular relationship thereto but which is so balanced as to assume an angular relationship with respect to the rod thereby to clutch the same when suspended solely from the rod, a stop for limiting the movement of the device and cooperating therewith in such manner as not to disturb the clutching of the rod by said device, a second stop movable into the path of the device and coacting therewith in such manner as to release the device from the rod, and means for supporting the device when in normal position in perpendicular relationship to the rod, said means being arranged to be engaged and moved by the wick when the latter is elevated thereby to permit the device to assume other than perpendicular relationship to the rod.
15. 11. In a burner of the character described, the combination of a supporting structure involving a wick guide, a wick movable therein, a member movably supported by the structure and operatively connected to the wick and through which the wick is raised and lowered, a lever pivotally supported by the structure and extending in juxtaposition to the member and having a part disposed within the path of the wick whereby the lever is tilted when the wick is elevated, a device normally resting upon the lever, the device being free from the aforesaid member when in such position but acting to attach itself to the member when shifted from normal position by the swinging of the lever, and means for limiting the movement of the device.

20. 12. In a burner of the character described, the combination of a supporting structure involving a wick guide, a wick movable therein, a member movably supported by the structure and operatively connected to the wick and through which the wick is raised and lowered, a lever pivotally supported by the structure and extending in juxtaposition to the member and having a part disposed within the path of the wick whereby the lever is tilted when the wick is elevated, a device normally resting upon the lever and having an aperture through

which the aforesaid member is freely movable when the device rests upon the lever, the device acting to clutch itself to the member when shifted from normal position by the swinging of the aforesaid lever, and means for limiting the movement of the device.

13. In a burner of the character described, the combination of a structure incorporating a wick guide, a wick supported therein for vertical movement, wick raising mechanism supported by the structure, operative connections between said mechanism and the wick, said connections involving a vertically movable rod, a lever pivotally supported by the structure and having a part normally projecting into the path of the wick so as to be engaged by the wick when the latter is elevated to swing the lever upon its pivot, a device normally supported by the lever in perpendicular relationship to the rod, the device having an aperture through which the rod extends and is free to move therein, a rocker arm pivotally supported by said device and having an aperture through which the rod extends, the aperture being of such size as to allow free relative movement between the arm and rod when the arm is substantially perpendicular to the rod, the arm clutching the rod when in other than perpendicular relationship thereto, means tending to move the rocker arm with respect to the device thereby to cause said arm to clutch the rod, the aforesaid lever having a part cooperating with a part of said arm when the parts are in normal position to maintain the arm perpendicular to the rod, and a stop for limiting the movement of the device.

14. In a burner of the character described, the combination of a structure incorporating a wick guide, a wick supported therein for vertical movement, a wick raising mechanism supported by the structure, operative connections between said mechanism and the wick, said connections involving a vertically movable rod, a lever pivotally supported by the structure and having a part normally projecting into the path of the wick so as to be engaged by the wick when the latter is elevated to swing the lever upon its pivot, a device normally supported by the lever in perpendicular relationship to the rod, the device having an aperture through which the rod extends and is free to move therein, a rocker arm pivotally supported by said device and having an aperture through which the rod extends, the aperture being of such size as to allow free relative movement between the arm and rod when the arm is substantially perpendicular to the rod, the arm clutching the rod when in other than perpendicular relationship thereto, means tending to move the rocker arm with respect to the device thereby to

cause said arm to clutch the rod, the aforesaid lever having a part cooperating with a part of said arm when the parts are in normal position to maintain the arm perpendicular to the rod, a stop for limiting the movement of the device, and a member movably supported by the structure and shiftable into a position to engage the rocker arm, such engagement of the member with the arm tending to shift the arm into perpendicular relationship to the rod.

15. In a burner of the character described, the combination of a structure incorporating a wick guide, a wick adjustable therein, wick raising mechanism supported by the structure, operative connections between said mechanism and the wick, said connections involving a member that is movable with the wick, a device movable in the direction of movement of said member and connectable to said member, means arranged to be engaged and moved by the wick when the latter is elevated for effecting connection of the device with the member, a stop movably supported by the structure and shiftable from effective to ineffective position, the stop when in effective position serving to arrest movement of the device, and a flame spreader for application to the burner and serving when applied to retain the aforesaid stop in effective position.

16. In a burner of the character described, the combination of a structure incorporating a wick guide, a wick adjustable therein, wick raising mechanism supported by the structure, operative connections between said mechanism and the wick, said connections involving a member that is movable with the wick, a device movable in the direction of movement of said member and connectable to said member, means arranged to be engaged and moved by the wick when the latter is elevated for effecting connection of the device with the member, a stop movably

supported by the structure and shiftable from effective to ineffective position, the stop when in effective position serving to arrest movement of the device, a flame spreader for application to the burner and serving when applied to retain the aforesaid stop in effective position, and an abutment supported by the structure and whereby the aforesaid device is adapted to engage when the stop is in ineffective position, the engagement of the device with the abutment tending to disconnect the device from the member.

17. In a burner of the class described, the combination with the wick, of a member movable therewith, a device capable of limited movement in the direction of movement of said member, a clutch carried by the device for securing it to the member, means arranged to be engaged and moved by the wick when the latter is elevated, and operative connections between said means and the clutch whereby the clutch is actuated when the said member is moved by the wick.

18. In a burner of the class described, the combination of a structure incorporating a wick guide, a wick adjustable therein, wick raising mechanism supported by the structure, operative connections between said mechanism and the wick, said connections involving a rod, a device movable along the rod, a clutch carried by the device for securing it to the rod, a member arranged to be engaged and moved by the wick when the latter is elevated, operative connections between said member and the clutch whereby the clutch is rendered effective, when the said member is moved by the wick, and means for limiting the movement of the aforesaid device.

In testimony whereof, I hereunto affix my signature.

LEE S. CHADWICK.
